UNITED STATES PATENT OFFICE

WILLIAM D. SWART, OF NASHUA, NEW HAMPSHIRE, ASSIGNOR TO AMERICAN BOX & LUMBER COMPANY, OF NASHUA, NEW HAMPSHIRE, A CORPORATION OF NEW JERSEY

BOX CONSTRUCTION

Application filed August 19, 1931. Serial No. 557,990.

This invention relates to boxes and more particularly to those which are secured together by nails. In order to strengthen boxes of this kind the ends are sometimes reinforced as by metal straps passed there-around and secured thereto. This effectually prevents splitting of the box end when it is made in one piece, or separation of the parts when it is made of separate boards secured together. These metal straps when arranged on the outside of the box, however, interfere with the handling of the box, being liable to catch in neighboring boxes or other objects and being likely to cut or tear the hands of those who handle them. To avoid these objections the straps may be passed around the end boards only of the box and between them and the side, top and bottom members so that the straps are not exposed in the finished box. It is customary to supply to the nails which secure the parts of the box together some kind of cement which is softened by the heat generated when the nail is driven and which thereafter hardens and makes withdrawal of the nails difficult. It is found, however, when such coated nails are driven through the metal of the straps most of the cement is stripped off so that its utility is largely destroyed.

In accordance with this invention, therefore, the metal strap is provided with openings or slots between its side edges substantially wider than the thickness of the nails and of substantial length and preferably several times the length of the continuous spaces between the slots. The uncut margins of the strap afford the required reinforcement to the wood of the box, and even when the strap is positioned between the ends and other wall portions of the box where it is out of sight, the openings through the strap being of substantial length relative to the uncut portions insures that a substantial portion of the securing nails shall pass through the openings instead of through the metal itself. A relatively large proportion of the coated nails thus have their coating material unaffected by the presence of the strap so that adequate holding of the nails is insured even though some of the nails may

pass through the metal and have the cement coating stripped off. The uncut portions of the strap between the slots hold the marginal continuous portions spaced apart and provide portions through which nails may be driven to initially secure the strap to the box ends before the other wall members are secured thereto.

For a more complete understanding of this invention reference may be had to the accompanying drawing in which

Figure 1 is a perspective of a portion of the metal strap.

Figure 2 is a perspective of the same as it might be bent around the marginal edge of a box end.

Figure 3 is a perspective of a box showing the straps in place.

Figure 4 is a detail section on line 4-4 of Figure 3.

Figure 5 is a detail section on line 5-5 of Figure 4.

Referring to the drawing, the reinforcing strip material, as shown best in Figures 1 and 2, comprises a metallic strip 1 having slots 2 between uncut and continuous side margins 3. These slots are spaced by uncut portions 4 which are relatively short with respect to the lengths of the slots 2 so that in any substantial length of the strapping the aggregate slot length is substantially greater, preferably several times as great, as the aggregate lengths of the uncut portions between the slots. These uncut portions hold the side margins 3 spaced apart and also furnish convenient portions through which securing nails 6 may be driven to initially secure the strapping material to the edges of the desired wall portions of the box.

In Figure 2 a piece of this strapping is shown as bent to conform to three sides of the edge of a box end, holes at 5 being shown through which the nails 6 for securing the straps in position before the neighboring wall members of the box are secured thereto may be driven. Such holes may be pre-formed if desired, but usually the strapping material is of such thin stock as to permit the nails to be driven directly there-through without difficulty.

- The strapping may be applied about the edges of the box ends as shown in Figure 3, being secured in position initially thereto as by the nails 6 as shown best in Figure 4. 5 The other wall members of the box which are intended to overlap the edges of the end member 7 may then be placed in position and secured by the nails 8, preferably cement coated, which are driven through the outer 10 wall members such as the sides 9 and bottom 10 into the end 7. These may be driven spaced as desired and substantially midway of the thickness of the end wall 7, so as to come between and out of contact with the 15 uncut marginal portions 3 of the strapping. Due to the much greater aggregate proportion of slot length to the length of the uncut portions between the slots the nails may be driven wherever desired along the margins of the upper wall members with the assurance that a substantial portion of them will pass through the slots of the strapping rather than through the uncut portions 4. They will thus be out of contact with the 20 metal portion of the strapping so that their cement coatings will not be affected thereby and full holding power will be available. The position of these nails, for example, are as shown in Figures 4 and 5. While occasionally a nail may pass through the uncut portion 4 of the strapping, nevertheless the proportion of nails which will be so driven to those which are driven through the slots will be so small that no serious weakening of 25 the box will result therefrom. 30
- By this construction it will be seen that it is feasible to reinforce the box by strapping applied inwardly of the outer wall portions where there is no danger of it catching in 35 surrounding packages or interfering with proper handling but at the same time the desirable results following the use of cement coated nails may be realized to a very substantial extent. 40
- 45 From the foregoing description of an embodiment of this invention it should be evident to those skilled in the art that various changes and modifications might be made without departing from the spirit or scope 50 of this invention as defined by the appended claims. 55

I claim:

1. Reinforcing strapping for boxes which comprises a metallic strip provided with 55 slots of substantial width arranged lengthwise between continuous side margins, the total slot length being substantially greater than the total length of the portions between said slots. 60
2. A box having wall members secured to its ends by cement coated nails, and reinforcing metallic strapping interposed between said members and ends and having slots of substantial length between continuous side margins spaced substantially wider 65

than the nail thickness and spaced by relatively short portions, the major proportion of said nails extending through said slots and out of contact with said strapping. 70

In testimony whereof I have affixed my signature.

WILLIAM D. SWART.
